UNITED STATES PATENT OFFICE.

GEORGE BECKER AND NATHAN WOLFF, OF NEW YORK, N. Y.

SHIRT.

1,046,049.

Specification of Letters Patent.

Patented Dec. 3, 1912.

Application filed December 4, 1911. Serial No. 663,904.

To all whom it may concern:

Be it known that we, GEORGE BECKER and NATHAN WOLFF, both citizens of the United States, residing in the borough of Manhattan, city, county, and State of New York, have invented certain new and useful Improvements in Shirts, of which the following is a specification.

Our invention, while applicable to the sleeves of garments generally, is especially designed for shirt sleeves, the object being to afford what may be designated as a reinforced extension sleeve,—the reinforcing being for the purpose of strengthening and preserving the attachment between sleeve and wrist band or cuff, as the case may be,—and the extension being for the purpose of adapting the garment to the varying requirements of customers. In other words our improvements relate particularly to what are known as "ready-made" shirts carried in stock by the retail trade. As heretofore obtainable in the market the cuffs or the wrist bands of these shirts have been attached directly to a single thickness or ply of the sleeve cloth, the sleeves themselves being of prescribed length, and the shirts being made of standard sizes in which the length of sleeve varies about two inches as between sizes. This construction necessitates the extension of the sleeves for a customer relatively long of arm as compared with chest or neck measurement, for instance, such change causing delay, expense and inconvenience, and involving the detaching of the cuffs or wrist bands, and the insertion of strips between them and the sleeves, resulting in a "patched" and unsightly appearance. Furthermore, the starch applied to the cuff or wrist band during the laundrying of the garment is apt to over-lap the cuff or wrist band and extend to the adjacent edge of the sleeve to which the cuff or wristband is attached, so that when the sleeve at line of attachment is only of a single ply or thickness of cloth as heretofore, the latter is rendered brittle by the ironing process, and the cuff or wrist band soon breaks away, in whole or in part, from the sleeve, rendering the shirt defective and useless long before the rest of the garment is impaired or worn out. These difficulties we obviate by our invention the object of which is to provide each sleeve

with a separately formed auxiliary extensible reinforcing band of special construction to which the cuff or wristband is directly and permanently attached. This auxiliary band, forming practically part of the shirt sleeve and interposed between the main portion thereof, and the cuff or wristband, performs the double function of reinforced means of attachment between cuff or wristband and sleeve, and also of means for extending the length of the sleeve when necessary without detaching the cuff or wristband, all as hereinafter fully set forth and claimed specifically,—it being understood in this connection that the cuff and the wrist band are considered as equivalents of each other, varying only in width,—the ordinary wrist band being essentially a narrow cuff to which a detachable cuff may be attached in the usual manner, while the term "cuff" as herein used refers to a cuff attached permanently either directly or indirectly to the sleeve.

In the accompanying drawings, we represent more or less diagrammatically the construction and utility of our auxiliary extensible reinforcing band forming practically part of a shirt sleeve and interposed between the outer edge of the sleeve proper and the cuff, where the latter is permanently attached, or between said edge of the sleeve and the wrist band where a detachable cuff is to be used. In the sectional views the several thicknesses of material are represented by solid black lines, which are spaced apart for clearness of illustration.

Figure 1, is an elevation of our extensible reinforcing band strip partly broken away to show the inner fold, &c.; Fig. 2, a transverse section taken upon the plane of line $x-x$ Fig. 1; Fig. 3, is an elevation, partly broken away, showing our auxiliary band stitched to the sleeve along the line of subsequent severance; Fig. 4, is a section upon plane of line $y-y$ Fig. 3; Fig. 5, is an elevation showing the outer folds of our auxiliary band turned back to allow the stitching of the outer edge of the sleeve permanently to the edges of the inner extensible folds of said band; Fig. 6, is a transverse section upon plane of line $z-z$ Fig. 5; Fig. 7, is an elevation partly broken away, showing our auxiliary band in condition for attachment to a cuff or wrist band; Fig. 8, is a

transverse section upon plane of line 8—8 Fig. 7; Fig. 9, is an elevation representing an ordinary wrist band attached to our auxiliary extensible reinforcing band; Fig. 5 10, is an elevation representing an ordinary cuff permanently attached to our auxiliary extensible reinforcing band; Fig. 11, is a transverse section upon plane of line 11—11 Fig. 10; Fig. 12, is an elevation of the parts 10 shown in Fig. 11, with our auxiliary reinforcing band extended; Fig. 13, is a transverse section upon the line 13—13 Fig. 12; Fig. 14, is an elevation illustrating the operation of extension.

15 The gist of our invention consists in the specific form and construction of the extensible auxiliary reinforcing band B, interposed between an ordinary cuff C, or wrist band C', and an ordinary shirt sleeve S.

20 This auxiliary extensible reinforcing band B, is formed preferably of a single strip of material united transversely at the ends, as by the seam 1, (Fig. 1) thereby constituting an endless double band equal in length to 25 the width of the edge s, of the sleeve S, to which it is to be attached. One edge of the strip is turned inward to form the central extensible folds 2, 2. This preliminary structure is illustrated in Figs. 1 and 2.

30 The next step in the process of manufacture is to insert the edge s, of the sleeve S, between the extensible folds 2, 2, with its extreme edge parallel to and coinciding with the inner edges thereof, as shown in Fig. 4, 35 when the parts thus positioned are secured together by the line of stitching s', adjoining the bight between the outer folds 3, 3, and the inner extensible folds 2, 2. The outer sides 3, 3, of the band B, are then

40 folded back over the sleeve as illustrated in Figs. 5 and 6 and the extreme edge s, of the sleeve and extensible folds 2, 2, united by a line of stitching 4. Next the outer sides 3, 3, of the band B, are again folded 45 outward into their former positions with their edges protruding beyond the extensible folds 2, 2, as shown in Figs. 7 and 8. This leaves the line of stitching 4, and the inner edge s, of the sleeve S, and the inner edges

50 of the extensible folds 2, 2, inclosed by said outer sides 3, 3, of the band, but free and unattached thereto except in so far as the line of stitching s', hereinbefore referred to, is concerned. An ordinary cuff C, or if the 55 shirt is designed for use with detachable cuffs, an ordinary wrist band C', is now sewed to the outer edges of the outer folds 3, 3, of our auxiliary extensible reinforcing band B, in any suitable or well known manner,—that shown in Figs. 10 and 11 consisting in inserting the said outer edges of the

55 folds 3, 3, between the folded inner edges of the cuff C, or wrist band C', as the case may be, and uniting the parts by a line of 60 stitches 5, thereby permanently attaching 65

the cuff C, or band C', to our auxiliary band and thus indirectly to the sleeve S, of the shirt. This results in the finished product shown either in Fig. 9 or Fig. 10,—the diagram Fig. 11 showing the outer plies of the cuff spread apart, and the line 6, representing the line of stitching that unites the outer edges of the cuff fabric. The inner edge of the cuff or wrist band being thus attached to the outer edges of both of the outer folds 3, 3, of our auxiliary band B, the connection is obviously more secure than when the attachment is directly to a sleeve consisting of only a single thickness of material, because the main strain and tendency to tear is at or near this line of juncture between the stiff, starched cuff or wrist band, and the part to which it is sewed. Furthermore presuming that the starch in laundrying protruded over the inner edge of the cuff or wrist band and onto our auxiliary band B, it is likewise obvious that the double thickness of the latter would be an effective protection, constituting practically, to all intents and purposes, a part or continuation 80 of the cuff or wrist band, in which extension the stiffening caused by the starch would gradually blend and disappear before reaching the connection between our said auxiliary band and the single thickness S, of the 85 sleeve itself. In other words our auxiliary reinforcing band B, insures a flexible joint between sleeve and cuff or wrist band under all conditions, and thereby obviates 90 danger of brittleness and rupture between 95 cuff or wrist band and sleeve. This condition obtains whether our auxiliary reinforcing band B, is in its original form, or opened up to release the extensible inner folds 2, 2, to lengthen the sleeve. This latter operation 100 is effected by severing the line of stitching s', adjacent to the bight between the inner extensible folds 2, 2, and the outer folds 3, 3, and may be quickly, safely and conveniently accomplished by the insertion 105 of a sharp pointed knife between the sleeve S, and one of the extensible folds 2, thereby releasing said inner folds 2, 2, and increasing the width of our auxiliary reinforcing band by the added width of 110 said extensible folds 2, 2, as illustrated in Figs. 12, 13, and 14,—the seam 4, between said original extensible folds 2, 2, and the sleeve S, remaining intact, and effectually 115 uniting the parts. In this connection our auxiliary reinforcing band B, whether extended or in its original form, may be likened to a relatively strong, tough, but flexible coupling interposed between the stiff cuff C, or wrist band C', and the weaker 120 single-ply fabric of the sleeve proper S. In either form, whether extended or not, our auxiliary band affords a finished and attractive appearance, and adds to the strength and value of the garment. In its original 125 130

form the extensible folds 2, 2, are entirely isolated, concealed and protected, their presence not being obvious until required.

What we claim as our invention and desire to secure by Letters Patent is,

In a shirt sleeve, the combination with the sleeve and cuff or wrist band, of an auxiliary extensible reinforcing band separate from and interposed between them and 10 consisting of a single strip of material united at the ends and having outward folds to which the cuff or wrist band is attached and inner extensible folds to and between which the edge of the sleeve is attached,

said sleeve being also attached to the outer and inner folds of the auxiliary band by another line of stitching near the bight between said inner and outer folds of the auxiliary band, the severance of which latter line of stitching releases the extensible folds 15 of the auxiliary band and thereby lengthens the sleeve, as and for the purpose described.

GEORGE BECKER.
NATHAN WOLFF.
